UNITED STATES PATENT OFFICE

154,518

DESIGN FOR AN INSECT ELECTROCUTING TRAP

Richard H. Turk, Chicago, Ill.

Application July 15, 1947, Serial No. 140,305

Term of patent 7 years

(Cl. D31—3)

To all whom it may concern:

Be it known that I, Richard H. Turk, a citizen of the United States, residing at Chicago, in the county of Cook and State of Illinois, have invented a new, original, and ornamental Design for an Insect Electrocuting Trap, of which the following is a specification, reference being had to the accompanying drawing, forming a part thereof.

Fig. 1 is a front view of an insect electrocuting trap embodying my new design;

Fig. 2 is a bottom view of Fig. 1;

Fig. 3 is an enlarged cross-sectional view taken substantially on line 3—3 of Fig. 1;

Fig. 4 is a cross-sectional view taken substantially on line 4—4 of Fig. 3;

Fig. 5 is a side view of Fig. 1; and

Fig. 6 is a top view of Fig. 5.

Fig. 7 is a perspective view taken at a point slightly above and to the left of Fig. 1.

I claim:

The ornamental design for an insect electrocuting trap, substantially as shown.

RICHARD H. TURK.
